US0D1111565S

(12) **United States Design Patent** (10) **Patent No.:** **US D1,111,565 S**
Cheng (45) **Date of Patent:** **** Feb. 10, 2026**

(54) **AIR SEAT CUSHION**

(71) Applicant: **Guangzhou Yuanqi Dynamic Technology Co., LTD**, Guangzhou (CN)

(72) Inventor: **Kuihu Cheng**, Shenzhen (CN)

(73) Assignee: **Guangzhou Yuanqi Dynamic Technology Co., LTD**, Guangzhou (CN)

(**) Term: **15 Years**

(21) Appl. No.: **29/944,110**

(22) Filed: **May 24, 2024**

(30) **Foreign Application Priority Data**

Nov. 29, 2023 (CN) 202330783549.2

(51) **LOC (15) Cl.** **06-09**

(52) **U.S. Cl.**

USPC **D6/604**

(58) **Field of Classification Search**

USPC D6/595, 596, 604, 605, 601

CPC A47C 4/54; A47C 27/18; A47G 9/1027

Primary Examiner — Sanjeev Paul

(57) **CLAIM**

The ornamental design for an air seat cushion, as shown and described.

DESCRIPTION

FIG. 1 is a perspective view of an air seat cushion showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
